UNITED STATES PATENT OFFICE

WALTER B. PARMELE, OF MINNEAPOLIS, MINNESOTA

DISPLAY DEVICE

Application filed December 31, 1927. Serial No. 244,031.

This invention relates to new and useful improvements in electric display devices, and an object of the invention is to provide a device configurated to simulate a Christmas tree and having means for supporting it in an upright position, and a plurality of electric light bulbs being mounted in the member and laterally projecting therefrom and having means for projecting a plurality of natural 5 light rays onto the surface of the member to produce ornamental effects and designs.

A further object of the invention is to provide an electric display device comprising a back ground, preferably colored green and 15 having sockets therein adapted to receive electric light bulbs, each of which has the major portion of its surface coated or treated with a suitable material designed to substantially obstruct or interrupt the light rays, and 20 relatively smaller portions of the surface of each light bulb adjacent to the socket end thereof, being uncoated to permit natural light rays to be projected therethrough onto the back ground in the form of a series of 25 radial rays, the rays projected from each light bulb intersecting and mingling with those of the other light bulbs to provide a very attractive display.

A further object is to provide an upright 30 supporting member configurated to simulate a Christmas tree and having a plurality of rosettes of artistic designs and colors mounted therein and each provided with a socket adapted to receive an electric light 35 bulb, and the light bulbs having the major portions of their surfaces frosted or covered with a suitable translucent coating adapted to interrupt or diffuse the light rays, and relatively small portions of said coating being 40 removed from the surface of each light bulb adjacent to the socket end thereof, whereby natural uncolored light rays will be projected from the light source through such uncoated portions of the bulbs and onto the colored 45 rosettes and the background, thereby producing various combinations of artistic designs and effects upon the background.

A further and important object of the invention is to provide a light bulb having the 50 major portion of its surface coated or treated

with a suitable material adapted to substantially interrupt the passage of light rays therethrough, and portions of the light bulb's surface, adjacent to the socket end thereof, being uncoated, and the uncoated surfaces 55 being of different designs or patterns so that when the light rays are projected therethrough onto a suitable background, various illuminated designs and patterns will be projected thereon, thus producing a very attractive display. 60

Other objects of the invention will appear from the following description and accompanying drawings and will be pointed out in the annexed claims. 65

In the accompanying drawings, there has been disclosed a structure designed to carry out the various objects of the invention, but it is to be understood that the invention is not confined to the exact features shown as various changes may be made within the scope 70 of the claim which follows.

In the accompanying drawings forming part of this specification;

Figure 1 is an elevational view of a display device showing the improved light bulbs mounted thereon and diagrammatically illustrating an effect obtainable by projecting a plurality of natural light rays upon a suitable background; 75

Figure 2 is an enlarged detailed sectional view on the line 2-2 of Figure 1;

Figure 3 is a view showing the socket end of a light bulb and illustrating portions of the coating removed from the surface of 85 the light bulb to permit natural light rays to be projected from the light source onto a suitable background; and

Figure 4 illustrates a modified form of bulb mounting wherein ornamental rosettes 90 or shields are employed between the light bulb and the background.

The novel display device featured in this invention comprises an upright supporting member or background 2, preferably configurated to simulate a Christmas tree as shown. The background 2 may be constructed of plate-like material, such as composition board and is mounted in a base member 3, adapted to support it in an upright position. 100

A plurality of apertures 4 are provided in the back ground or member 2 in which flexible sleeves or bushings 5 are mounted as shown in Figure 2. These bushings are preferably of rubber and have a head 6 which is seated against the member 2 as shown.

Sockets 7, of ordinary construction, having conductors 8 and 9 electrically connected therewith, are frictionally mounted in the bushings. Each of these sockets is adapted to receive an electric light bulb 10.

An important feature of this invention resides in the novel construction or treatment of the light bulbs 10, which is such as to cause a plurality of light rays to be projected from each bulb onto the background 2. The surface of each light bulb is covered or treated with a suitable translucent material as indicated by the numeral 11 in Figure 2. The coating on the various bulbs

may be of different colors, if desired, such as, for example, the coloring used in the construction of light bulbs adapted for use in connection with Christmas trees. Portions of this coating are removed from the light bulb at the socket end thereof, as indicated at 12 in Figures 2 and 3. Through these uncoated portions which are preferably in the form of narrow slits, light rays may be projected from the light source of each bulb onto the background 2 which, preferably is colored green. The uncoated portions of the bulbs' surfaces may be made in various designs and figures so as to produce different

designs and effects upon the background. To further enhance the attractiveness of the display device, rosettes or shields 15, of various colors may be mounted back of the light bulbs, as indicated in Figure 4. The natural light rays projected through the transparent portions of the light bulbs, onto these colored rosettes or directly onto the background 2, produces a very attractive display. When the transparent portions of the bulbs' surfaces are in the form of narrow slits, radially disposed as shown in Figure 3, the natural light rays projected therethrough will tend to cross the light rays projected from adjacent bulbs, and will mingle therewith so as to produce upon the background various colored designs and effects.

When vari-colored bulbs are used in connection with this device, unusually brilliant combinations of shades and shadows are produced upon the background. The long needle-like rays of natural light projected through the transparent slits in the bulbs' surfaces onto the colored background produce a very attractive effect, the long narrow rays radiating from the light source in all directions, and the light rays from one bulb intersecting those of other bulbs. Each needle-like ray is also clearly defined upon the background. This novel display device therefore provides a very attractive decora-

tion, well adapted for use as an interior decoration for homes, store windows, banks, hotel lobbies, theatres and many other places. The device is also made water-proof so that it may be used as an exterior decoration, when desired, in the form here shown, and, is particularly well adapted for use as a decoration during the holiday season.

I claim as my invention:

A flat member having spaced-apart cylindrical apertures therein, the axes of which are disposed in parallel relation, a rubber bushing adapted to be fitted into each aperture, an annular shoulder at one end of each bushing adapted to engage one face of the member, said bushings being frictionally retained in said apertures, and each bushing having a cylindrical bore adapted to receive and support a device such as an electric light bulb.

In witness whereof, I have hereunto set my hand this 27th day of December, 1927.

WALTER B. PARMELE.
